(57) **CLAIM**

The ornamental design for a chair with stylized legs, as shown and described.

DESCRIPTION

FIG. 1 illustrates an oblique perspective view of a chair with stylized legs;

FIG. 2 illustrates a front perspective view of the chair with stylized legs;

FIG. 3 illustrates a side view of the chair with stylized legs;

FIG. 4 illustrates a rear perspective view of the chair with stylized legs; and,

FIG. 5 illustrates a bottom view of the chair with stylized legs.

The right side of the chair, which is not shown in the drawings, is a mirror image of the left side shown in FIG. 3. The top side of the chair does not include any distinctive features which are not otherwise shown in the drawings.

1 Claim, 5 Drawing Sheets

FIG. 1

FIG. 2

FIG. 3

FIG. 4
